HAZLEHURST R. NOYES, OF LOS ANGELES, CALIFORNIA

FOLDING FURNITURE

Application filed February 5, 1929. Serial No. 337,702.

This invention relates to articles of furniture, such as have legs, and especially to tables, stands, benches, chairs, or the like.

It is one of the objects of my invention to make it possible to fold the legs of such a device in a compact and convenient manner.

Folding card tables have been used, in which the legs fold under the table top. Experience shows that such devices are unsatisfactory because they are weak and liable to collapse; and furthermore, the unfolding of the legs takes a substantial amount of time. My invention obviates all these difficulties, by providing a strong and rigid structure when the legs are extended, and yet one that can be very readily folded and unfolded without the need of great dexterity or skill. Such a folding device is therefore especially adapted for use in the ordinary household, as it can readily be manipulated by women or children.

The folding feature can of course be applied to many varieties of furniture such as mentioned heretofore. In fact, the legs when partly unfolded can serve as rests for supporting the top in a vertical, or a near vertical position, as for a fire place screen. Furthermore, the particular materials from which the device can be made are not restricted, as metal as well as wood is readily adaptable for my purpose.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention, but it is to be understood that this detailed description is not to be taken in a limiting sense, since the scope of my invention is best defined by the appended claims.

Referring to the drawings:

Figure 1 is a bottom view of an article of furniture, folded, that incorporates my invention;

Fig. 2 is a sectional view, taken along plane 2-2, but shown with the legs in unfolded

position, and with the legs partly broken away, to save space;

Fig. 3 is a detail section taken along plane 3-3 of Fig. 1;

Fig. 4 is a detail section, taken along plane 3-3 of Fig. 2;

Fig. 5 is a detail section, taken along plane 2-2 of Fig. 2;

Fig. 6 is a detail section, taken along plane 6-6 of Fig. 2;

Fig. 7 is a side elevation of the device with the legs extended;

Fig. 8 is a detail section, taken along plane 8-8 of Fig. 2; and

Figs. 9, 10 and 11 are diagrammatic views illustrating the manner in which the device can be folded and unfolded.

I show in the present instance, a folding table made from wood; but the principal can be utilized for other articles of furniture, made from wood or other materials. The top 21 has a pair of parallel cleats or slides 22, 23 that are adjacent two opposite edges of the top and on the bottom surface thereof. These cleats serve to strengthen the top 21, and also as guides for the folding leg structure as hereinafter described.

Near the left hand edge of the top 21 is a cross cleat 24 that connects the cleats 22, 23 as by dovetailing. A leg structure is hinged to this cleat 24. This structure includes the two legs 25, 26 (Figs. 1, 2, and 4) and a connecting apron or board 27. The hinges 28 for this structure are located on the inside surfaces of the cleat 24 and board 27, as clearly shown in Figs. 2 and 4. It is apparent that legs 25 and 26 can be folded to be adjacent the top 21 (as shown in Figs. 1, 3, and 9) or else extended to be perpendicular to the top 21 (as shown in Figs. 2, 4, and 11).

The other leg structure forming the other two legs of the table, includes an apron or board 29 (Figs. 1, 2, 3 and 5) to which are fastened the leg pieces 30, 31. All of the legs are shown as square in section, although this form is not essential. The structure 29-30-31 is also foldable; it can be slid beneath the other leg structure 25-26-27 by the aid of the construction now to be detailed.

Each of the cleats 22, 23, has a groove such as 32 (Figs. 1, 3, 4, 5, and 8) on its inside face. In these grooves are freely slideable the pins or projections 33 (Figs. 3, 5, 8, 9, 10 and 11) that extend outwardly from the leg structure 29—30—31. This leg structure, which is otherwise entirely unattached to the top 21, can therefore be slid into a position such that the legs 30, 31 are parallel with and under the top 21, as shown in Figs. 1 and 3; or else the structure 29—30—31 can be moved outwardly from beneath top 21, as indicated in Fig. 9, by the arrow 34. The slots 32 are just long enough to limit this outward movement in order to bring the structure 29—30—31 adjacent the right hand edge of top 21, as shown in Figs. 9, 10, and 11. Then the structure can be pivoted about the axis of pins 33 to cause legs 30, 31 to assume a position perpendicular to top 21, as indicated most clearly in Figs. 2 and 11.

In fact, the proper positioning of legs 30, 31 can be accomplished by the aid of gravity. If the folded table is held in the vertical position of Fig. 9, the legs 30, 31 will be allowed to fall to the position there shown, and as limited by the engagement of pins 33 with the end of grooves 32. Then the top 21 can be turned to a horizontal position, in a direction shown by arrow 35 (Fig. 10). An intermediate position in the process of turning is indicated in Fig. 10, the legs 25, 26, 30, 31 hanging freely in a vertical direction under the influence of gravity about their respective pivots. The completed movement of the top is shown in Fig. 11, the legs in that case assuming the vertical relation to the table top 21. I shall hereinafter describe how all four legs can be clamped either in this vertical position, or in the folded position of Fig. 1.

In order to limit the swing of leg structure 29—30—31 to the vertical position of Figs. 2, 7 and 11, I preferably provide a cross bar 36 (Figs. 1, 2, 5, 7, and 8) that is fastened at each end to the bottom surface of cleats 22, 23 as shown most clearly in Figs. 5 and 7. In the extended position of legs 30, 31, this bar contacts with the inner surface of these legs, as indicated in Fig. 3, and prevents these legs from swinging under the top 21 in a clockwise direction about the axis of pins 33.

I shall now describe the means whereby the legs 25, 26, 30, and 31 are held in extended position. Along the bottom surface of the cleats 22, 23, there are pivoted the folding apron members 37, 38, as by the aid of the spring hinges 39. In Figs. 1 and 3, the aprons are shown as folded back to a position substantially parallel with the top 21, against the resilience of spring hinges 39. In this position, these hinges urge the edge of the apron toward folded legs 25, 26 to hold them in folded position. In order to ensure against the legs being jarred out from the

folded position, a retaining piece 40 of leather or metal can also be fastened on each of the aprons 37 and 38 that engages the exposed outer surface of legs 25, 26. This piece 40 is urged downwardly against the leg; but by rotating the aprons 37, 38 toward the top 21, the piece 40 is freed from the leg, and the table can be unfolded.

When the legs 25, 26, 30, 31 assume the unfolded position, the aprons 37, 38 are released so as to engage the top portions of the legs. Each apron has grooves, such as 41 as shown most clearly in Figs. 1 and 6, that are arranged to accommodate the legs when these legs are in extended position. In this way, the legs are held firmly against collapsing when the table is in use, by the action of the shoulder in grooves 41 holding the legs in spaced relation.

As shown most clearly in Figs. 3 and 4, the aprons 37, 38 have a rabbeted portion 42 forming a shoulder that contacts with the inner surface of the cleats 22, 23 when in extended position. The aprons also are grooved as shown at 43 (Figs. 1 and 2) to permit the passage of rod 36. A resilient bumper or buffer pad 44 is provided on the inner surface of cross piece 27 connecting legs 25 and 26, which contacts with the cross piece 29 when the table is folded.

Assuming that the table is in the folded position of Fig. 1, it can be easily unfolded as follows: Holding the table in a vertical position as indicated in Fig. 9, the hands can be used to press aprons 37, 38 toward the top 21. This releases the leg structures, permitting legs 30, 31 to slide to the position of Fig. 9. Then the top 21 can be turned to the horizontal position of Fig. 11, the table set on the floor, and finally the aprons 37, 38 can be released to spring into the position of Figs. 4, 5, or 7.

Folding the table is accomplished as follows: While the table is resting on the floor, the aprons 37, 38 are grasped by the hands and held in the position of Fig. 3. The top 21 is then tilted to a vertical position. The table will then assume the position of Fig. 9. Resting the ends of legs 30, 31 on the floor, the top 21 can then be pushed downwardly so as to bring these legs beneath legs 25, 26, and then aprons 37, 38 can be released to clamp the leg structures in their folded position.

One of the advantages of the present invention resides in the fact that the leg structures can be clamped in slanting positions by the engagement of the rabbet portion 42 of aprons 37, 38 with the side surfaces of the legs. Thus the table top 21 can be supported by the legs in a position departing from the horizontal. In fact, a vertical position can be obtained by causing only one of the leg structures to assume a slanting position. In

such vertical position of the top, it can be used as a fire screen.

I claim:

1. In an article of the character described, 5 a top member, a leg structure hinged to the top member and arranged to be folded so as to extend beneath the top member, another leg structure having a pin and groove connection with the top member, whereby it can be slid in folded position between the top member and the first leg structure, and resilient means for holding the leg structures in either open or closed position.

10 2. In an article of the character described, 15 a top member, a pair of leg structures, each having a pair of legs, one of said structures being hingedly supported on the top member, and the other having a sliding and pivotal connection with the top member, and arranged to be disposed in folded position between the other structure and the top member, and means for holding the leg structures in extended position, comprising apron boards foldable to hold the leg structures in 20 spaced relation.

25 3. The combination as set forth in claim 2, with the addition of spring hinges resiliently urging the apron boards to active position.

30 4. In an article of the character described, a top member, a leg structure hinged to the top member and arranged to be folded so as to extend beneath the top member, another leg structure having a pin and groove connection with the top member, whereby it can be slid in folded position between the top member and the first leg structure, and resilient means for holding the leg structures in either open or closed position, comprising 35 folding apron boards and spring hinges for 40 said boards.

5. In an article of the character described, a top member, a pair of cleats fastened thereto adjacent opposite edges, each of said cleats being provided with a groove, the grooves facing each other, a leg structure hinged adjacent one end of the cleats, another leg structure having pins engaging in the grooves and arranged to be slid along the grooves, and 50 folding apron boards for holding the leg structures either in open or closed positions.

55 6. In an article of the character described, a top member, a pair of cleats fastened thereto adjacent opposite edges, each of said cleats being provided with a groove, the grooves facing each other, a leg structure hinged adjacent one end of the cleats, another leg structure having pins engaging in the grooves and arranged to be slid along the grooves, folding 60 apron boards for holding the leg structures either in open or closed positions, and a stop member arranged transversely of the cleats for limiting pivotal motion of the said other leg structure.

65 7. In an article of the character described,

a top member, a leg structure hingedly supported on the top member and having legs arranged to swing downwardly perpendicularly to the top member, another leg structure having a sliding and pivotal connection with the top member, and having legs arranged to swing downwardly perpendicularly to the top member, and means for holding the leg structure in extended position.

70 8. In an article of the character described, 75 a top member, a leg structure hingedly supported on the top member and having legs arranged to swing downwardly perpendicularly to the top member, another leg structure having a sliding and pivotal connection with the top member, and having legs arranged to swing downwardly perpendicularly to the top member, and hinged apron members, one on each side of the top member, for holding the leg structures in extended position.

85 In testimony whereof I have hereunto set my hand.

HAZLEHURST R. NOYES.
